UNITED STATES PATENT OFFICE.

ALBERT B. RUTLAND, OF COCO SOLO, CANAL ZONE.

BLOCK AND TACKLE.

Application filed February 26, 1926. Serial No. 90,859.

This invention relates to blocks and tackle, and more particularly to a manner of arranging and supporting a plurality or group of pulleys, whereby objects or weight may be lifted with a minimum of power.

The nature and advantages of the invention will be better understood when the following detailed description is read in connection with the accompanying drawing, the invention residing in the construction, combination and arrangement of parts as claimed.

In the drawings forming part of this application, like numerals of reference indicate similar parts in the several views, and wherein:

Figure 1 is a view of a plurality of pulleys supported on one type of frame.

Figure 2 is a diagrammatic view showing how the cable is trained over the various pulleys.

Figure 3 is an elevation partly in section, illustrating a modification.

Figure 4 is an elevation illustrating a still further modification.

Referring to the drawings, and particularly Figures 1 and 2, 10 indicates generally the frame upon which a plurality of pulleys are supported, the frame being strengthened by bracing elements 11. Supported by the ends of this frame 10 is a cross bar 12 from which is suspended spaced blocks 13, each of which has journaled therein a plurality of pulleys 14. The blocks are suspended from the bar by apertured lugs 15, and surrounding this bar are sleeves 16 which engage said lugs and hold the blocks from movement longitudinally of the bar. Depending from the blocks are apertured lugs 17 which are connected by a bar 18 arranged parallel with the bar 12, and surrounding the bar 18 is a sleeve 19 which contacts the lugs 17 and holds the block against movement. It is, of course, to be understood that there are two of the frames 10 used with the cable shown in Figure 2, the lower frame (not shown) being arranged in a position just the reverse from that shown in Figure 1. The cable 20 is then trained over the pulleys of the respective groups in the manner clearly shown in Figure 2, wherein it will be noted that one end of the cable is trained over the pulley 21 of one of the lower pairs of pulleys, and then extended upwardly over the pulley 22 arranged diagonally opposite the

pulley 21, thence downwardly over the pulley 23, and thence over the pulley 24 arranged diagonally opposite the pulley 23; the cable is then continued downwardly over the other pulley of the pair 23 and thence upwardly over the other pulley of the pair 22, and thence downwardly over the other pulley of the pair 21, and finally over the remaining pulley of the pair 24. By reason of this construction and arrangement, objects or weight can be lifted with a minimum of power, and with considerably less power than block and tackle constructions with which I am familiar.

In Figure 3 the cross frame 50 is centrally formed at its top with a substantially V-shaped extension 51 which merges into a hook 52, there being a reinforcing rib 53 between the rib and the frame 50. The frame is really in the nature of a cross sectional rod of metal casting and has its ends reduced and threaded, as at 54. The reduced ends support thereon the eye portions 55 of blocks 56, the said eyes 55 being contacted by washers 57 which in turn are contacted by nuts 58 which are screwed on the said ends 54. The frame 50 is also centrally formed with a depending hook 59 which may be engaged by the eye of another block 56.

In Figure 4 the construction is substantially similar to that disclosed by Figure 3, the frame 60 having revolvably supported on its reduced ends blocks 61, the said frame having its bottom portion centrally formed with depending ears 62 between which there is received the eye of a block 63, and passing through the ears 62 and the eye in the block 63 there is a bolt member 64 which is engaged by a nut 65.

While it is believed that from the foregoing description the nature and advantages of the invention will be readily apparent, I desire to have it understood that I do not limit myself to what is herein shown and described, and that such changes may be resorted to when desired as fall within the scope of what is claimed.

Having thus described the invention, what is claimed as new, is:

A device of the class described comprising two pairs of upper pulleys spaced apart, two pairs of lower pulleys spaced apart and a cable adapted to have one end fastened to a support and passed over a lower pulley of the right hand pair, then upwardly over an

upper pulley of the left hand pair, then downwardly over a lower pulley of the left hand pair, then upwardly over an upper pulley of the right hand pair, then downwardly over the second pulley of the lower left hand pair, then upwardly over the second pulley of the upper left hand pair, then

5 downwardly over the second pulley of the lower right hand pair and then upwardly over the second pulley of the upper right hand pair.

In testimony whereof I affix my signature.

ALBERT B. RUTLAND.
